UNITED STATES PATENT OFFICE

FRANK H. SCHWERIN, OF BELLEVUE BOROUGH, PENNSYLVANIA, ASSIGNOR TO THE DUFF-NORTON MANUFACTURING COMPANY, OF PITTSBURGH, PENNSYLVANIA, A CORPORATION OF PENNSYLVANIA

LIFTING JACK

Original application filed March 2, 1928, Serial No. 258,495. Divided and this application filed February 21, 1929. Serial No. 341,619.

The object of the invention is to provide a simple, convenient and effective operating connection between a rotary actuating element of a jack and a rotary handle, whereby 5 the handle is separable and will drive the actuating element with the axes angularly out of alignment. A further object is to cause the handle to be retained in engagement with the jack, so as to enable the handle to be 10 used both in positioning the jack beneath an automobile or elsewhere and in withdrawing it.

In the accompanying drawings forming part hereof:

15 Fig. 1 is a side elevation of a jack with a long extension handle connected with the jack by means of the invention, intermediate portions of the handle, constituting most of its length, being broken out;

20 Fig. 2 is a sectional view of the part on the inner end of the separable handle, shown in a position in relation to Fig. 1 in which it can be entered into engagement with the jack;

25 Fig. 3 is an end view of the head on the actuating element of the jack illustrated in Fig. 1; and

Fig. 4 is an enlarged transverse section taken on the line 4—4 of Fig. 1.

The jack illustrated is of the construction 30 claimed in my copending application Serial No. 258,495, filed March 2, 1928, of which this application is a division. It has a base 2, a top 17, geared toggle links 6, 7, 8, 9, and a right and left-hand screw-shaft 21 which 35 passes through nuts located at the elbows of the toggles. The invention to be described is not limited, however, to the particular type of jack.

40 The rotary actuating element, or shaft, 21 is provided with a squared, or generally polygonal or non-circular, head 23. The faces of this head are convex, or more or less circularly arcuate, in the longitudinal direction, and their inner portions are formed 45 with longitudinal grooves 24.

50 A separate extension handle 25 has a fork socket 26 on its inner end, the sides of this fork having inwardly projecting pins or 55 projections 27 adapted to engage the grooves 24. The fork 26 can be entered on and re-

moved from the narrow or shank portion of the part 23 when the axes of the parts are at a decided angle, but when the handle is straightened more or less in line with the rotary actuating element of the jack, the pins 55 27 in engagement with the grooves 24 retain the handle against coming off sideways and against being pulled off endwise. Rotation of the handle will thus raise and lower the jack, and the handle can also be used to push 60 the jack into place and to draw it out after the operation is over. The longitudinal convexity of the faces of the head 23 enables the handle to be held at a range of inclinations and still to operate the member 21. 65

The handle may be composed of two sections 30 and 31 that can be taken apart, the sections being connected by a sleeve 28 fixed to one section and having slots to be engaged by pins 29 on the other section. The section 70 31 can be long enough to serve as a handle for withdrawing the jack.

It will naturally suggest itself that the parts 23 and 26 might be reversed with respect to the jack and handle. 75

What I claim as new is:

In a lifting jack, a separable connection between a rotary actuating element and an extension handle element, comprising a squared head connected with one of said 80 elements, the faces of said head being convex in the longitudinal direction and having longitudinal grooves in their inner portions, and a fork connected with the other of said 85 elements and having internal retainer projections to engage said grooves, the relation being such that the handle element is entered on and removed from the jack when at a decided angle and is retained against disengagement when straightened more or less in 90 line with the actuating element. 95

FRANK H. SCHWERIN.
